FISH LURE

Paul E. Karisch, 6315 Tulsa St., Houston 18, Tex.

Filed Nov. 12, 1963, Ser. No. 77,355

Term of patent 14 years

(Cl. D31—4)

FIG. 1.

FIG. 3

FIG. 2.

FIG. 1 is an isometric view of a fish lure showing my new design;

FIG. 2 is a side elevation thereof; and

FIG. 3 is a fragmentary bottom plan thereof.

I claim:

The ornamental design for a fish lure, as shown.
